UNITED STATES PATENT OFFICE.

FRANK C. GOODWIN, OF CHELSEA, MASSACHUSETTS.

DESIGN FOR A CAMPAIGN-TORCH.

SPECIFICATION forming part of Design No. 15,206, dated August 5, 1884.

Application filed June 16, 1884. Term of patent 3½ years.

To all whom it may concern:

Be it known that I, FRANK C. GOODWIN, of Chelsea, in the county of Suffolk and State of Massachusetts, have invented a new and original Design for a Campaign-Torch, of which the following is a specification.

The nature of my design is fully shown in the accompanying drawing.

The design consists in a torch the body of which has the form and configuration of a pine-cone, as shown in the drawing, combined with a suitable support or bracket.

The proportions of the body and number of imitation petals or seeds may be varied without departing from the spirit of my design.

I claim—

The design for a campaign-torch, consisting in the combination of a torch having the shape and configuration of a pine-cone with a support or bracket, as set forth.

In testimony whereof I have signed my name to this specification, in the presence of two subscribing witnesses, this 14th day of June, 1884.

FRANK C. GOODWIN.
